UNITED STATES PATENT OFFICE.

RICHARD H. COBLEY, OF SEATTLE, WASHINGTON.

OIL-BURNER.

1,114,712.

Specification of Letters Patent. Patented Oct. 26, 1914.

Application filed November 28, 1913. Serial No. 308,637.

To all whom it may concern:

Be it known that I, RICHARD H. COBLEY, a citizen of the United States, and resident of Seattle, King county, Washington, have invented certain new and useful Improvements in Oil-Burners, of which the following is a specification.

My invention relates to improvements in oil burners and comprises certain novel parts and combinations of parts which will be hereinafter described and particularly pointed out in the claims.

The object of my invention is to simplify and improve the construction of devices of this character to make them cheaper, more lasting and reliable in use, and to make them more efficient.

In the accompanying drawings I have shown my invention in the forms of construction which are now preferred by me.

Figure 1 shows the bent pipe, which is used as the main conducting channel for the oil, in full lines, with the relative position of the cast body indicated by a dotted line outline. Fig. 2 is a central vertical section through the device. Fig. 3 is an elevation and partial section of the device, the plane thereof being at right angles to that used in Fig. 2. Fig. 4 is an elevation and partial section of a slightly modified type of construction.

The burner as herein illustrated, is designed particularly for insertion within stoves employed for domestic purposes. Such stoves may consist of a kitchen range, in which case two or more burners may be employed, or a heating stove, in which case, ordinarily, a single burner would be sufficient.

In Figs. 2 and 3 I have shown a construction at G, which is intended as a conventional representation of a grate, as for instance, a grate employed within a kitchen range. The construction of this grate is immaterial, as it is merely employed as a means for supporting the burner. Upon this grate I prefer to place a layer of material which will close all the draft openings in the grate, except such as will coöperate with the draft openings in the burner. For this purpose I have shown a sheet H of asbestos or equivalent material, which is placed on top of the grate. As a substitute therefor it is evident that a sheet of metal, or a layer of fire clay may be employed.

For purposes of description the burner

may be divided into three sections or parts, a lower part or base section 10, an annular or tubular upper section 12 which may be called the head of the burner, and connecting and supporting posts 11. This construction supports the upper section 12 at such a distance above the base 10 as to provide openings 13 between the two which extend entirely about the burner, except as interrupted by the posts 11.

The base 10 is provided with a primary oil receiving chamber 14, with which connects an oil supply pipe 15, which pipe extends downward through the grate. The oil supply to the burner first enters the chamber 14, which chamber is closed except for its connection with the oil supply pipe and with the passages in which the oil is gasified by the heat of the burner.

The oil passages referred to extend, one through each post 11 and thence, by a circuitous route within the walls of the upper annular or tubular section 12, to the top thereof. The main body of the burner is composed of cast iron, while the walls of the passage referred to and the formation of the channel of the desired shape in said upper portion of the burner, is secured by bending a piece of wrought metal tubing into the desired shape, placing this tubing into the mold, and then casting the body of the burner about the same.

A piece of tubing bent to the shape contemplated by the accompanying drawings is shown in Fig. 1, and the outline of the cast portion of the burner is shown in dotted lines. This tubing has a short section 20 at each end which is left straight, said ends extending vertically in the completed burner and being substantially parallel. These end sections lie within the body of the posts 11 in the completed burner and connect with the chamber 14 in the base section of the burner. Above this point the tube is bent into the form of a helix, forming coils 21 which lie within the walls of the tubular upper section 12 of the burner. The central portion 22 of the tube which connects the upper coil parts, extends across the upper end of the tubular section 12 of the burner, preferably as a low arch, as is clearly shown in the drawings, and is provided with a discharge orifice 23, located over the bore of the section 12. This orifice discharges the gas which has been produced from the oil by the heat to which it has been subjected.

in passing through the passages just described, directly downward into the bore 16.

The base section of the burner, in the form of construction preferred by me, has its upper surface somewhat concave or hollowed, so as to form a cup for the reception of a sufficient amount of oil, which may be discharged therein and burned in order to heat the burner up to such a temperature as will 10 properly gasify the oil, this being done only at the time of lighting the burner. This may be done by depressing the diaphragm which forms the roof of the chamber 14, as is shown by the depression 17, or by lowering 15 this diaphragm so as to leave a low flange or wall 18, extending about its periphery, or by doing both. This flange forms a priming cup of ample capacity for enough oil to thoroughly heat up the head or top 20 section 12 of the burner. By forming the burner so as to locate the priming cup between the base section 10 and the volatilizing head 12, it may be kept of sufficiently small height that there will be room for it 25 in the fire pot of the ordinary stove.

The base section 10 of the burner, is provided with bosses or ears, located at opposite sides thereof and containing air conveying passages. One of these, 3, is located 30 just without the outline of the tubular section 12, and extends upward to a level substantially conforming to that of the side opening 13. Care should be taken to provide a suitable connecting opening extending 35 through the grate and the layer H which is placed thereon so that it may be freely supplied with air. Outside of this, but preferably in the same lateral plane, the boss 30 is provided with a similar opening, which 40 serves as a supporting socket for a pipe 31, which extends upward and has its upper end bent and extending over the top of the burner, discharging its air supply into the bore of said tubular section, where it meets 45 the gas discharged from the orifice 23.

In Fig. 4 I have shown a construction in which a distinct and separable base member is employed. This base member 32 is provided with a cup-shaped depression 33, into 50 which the base of the main body of the burner enters. This depression 33 forms a supplementary receiver for the oil used to preliminarily heat the burner, in case an unusual amount chances to be discharged. It 55 is not intended that this should ordinarily be filled when starting the burner, as the cup formed by the flange 18 is ample in size and the annular head or tube 12 has ample volatilizing capacity. It is a safety cup intended to catch any overflow from the regular priming cup.

The base 32 carries the bosses 3 and 30, with their air conveying passages, instead of having the latter made as an integral 60 part of the main body of the burner. The

construction of the form shown in Fig. 4 is otherwise such as has been described.

The iron which is cast about the pipe 2, is used for two purposes. First, it constitutes a protective covering for said pipe, preventing it from being burned out by the heat of the flame, and second, it forms a heat storage reservoir which will better insure a sufficiently high temperature to gasify the oil to carry over times when the flame may be turned low.

This form of construction also serves a useful purpose in this way; to form passages of such character as are desired, within such a body of metal by an ordinary core, 80 would be very difficult and expensive. In addition, the walls of passages so formed would be rough and would be coated with sand and the material of which the core was formed, and particles of this would be liable 85 to dislodgment and to be carried up to the orifice 23, which might become thereby choked. By forming the walls of this passage of a tube about which the iron is cast, a smooth surfaced wall, free of any removable particles is obtained.

When in use the gas discharged from the orifice 23 is thrown forcibly downward into the central bore 16. Being mingled with the air coming through the pipe 31, this 95 bore is filled with flame, which issues through the openings 13 between the top and base, where it meets the air being introduced through the passages 3, which assists in completing the combustion.

What I claim as my invention and desire to patent is:

1. An oil burner for stoves comprising an integral casting having a base section containing therein a primary fuel receiving chamber and having a marginal upper flange forming a priming cup, said casting having an upper tubular section which is joined to the base by posts which are integral with each section and maintain said upper and lower sections somewhat separated, said upper section having oil flow channels in its wall each extending through its respective post to communication with the primary fuel receiving chamber of the base and at its upper end with the upper end face of the said upper section, and a tube connecting said channel ends and extending across the central chamber of the upper tubular section and having an axially placed hole discharging downward.

2. An oil burner for stoves comprising a base section having a primary oil receiving chamber and ears at opposite sides each provided with air conducting channels extending between its under and its upper surfaces, and other like channels adapted to form sockets for air conveying pipes, a tubular upper section integrally connected with and supported above the base by posts,

said tubular upper section and the posts containing channels extending from the primary oil receiving chamber to the upper end surface of the said tubular upper section, a 5 tube connecting the upper ends of said channels and extending across the central opening of said upper section and provided with an opening discharging downwardly into said central opening, the base section having 10 an upper marginal flange forming a priming cup, and air conveying pipes fit-

ting in the sockets of the base and extending upward to discharge adjacent the upper end of the opening in said upper tubular section.

15

In testimony whereof I have hereunto affixed my signature this 22d day of November, 1913.

RICHARD H. COPLEY.
